UNITED STATES PATENT OFFICE.

CHARLES H. QUARLES, OF CHARLOTTESVILLE, VIRGINIA, ASSIGNOR TO AMERICAN AUTOMATIC TRAIN CONTROL CORPORATION, OF BALTIMORE, MARYLAND, A CORPORATION OF MARYLAND.

TRAIN-CONTROLLING MECHANISM.

Application filed February 3, 1920. Serial No. 355,971.

To all whom it may concern:

Be it known that CHARLES H. QUARLES, a citizen of the United States, residing at Charlottesville, in the county of Albemarle 5 and State of Virginia, has invented certain new and useful Improvements in Train-Controlling Mechanism, of which the following is a specification.

This invention relates to an improved 10 valve device for use in conjunction with electro-pneumatic train-controlling mechanism.

In train-controlling mechanisms wherein 15 the operation of the air-brake is a feature, suitable devices are employed to effect an automatic venting of the train-line of the air-brake system, when the conditions on the road are such as to make it desirable to effect an automatic stoppage of the train.

20 The automatic venting of the train line of the air-brake system, as heretofore practiced in train-controlling mechanisms, either completely exhausts practically all pressure in the train-line, or so reduces the train-line 25 pressure that a considerable loss of time ensues before the train can proceed after getting an automatic stop application of the brakes, because the brakes cannot be released until the pressure in the train-line 30 has been restored sufficiently to effect such release of the brakes.

Moreover, if the train proceeds immediately upon the release of the brakes and before the pressures in the train-line and 35 other parts of the air-brake system are sufficiently recharged, then there is liability of the system lacking sufficient pressure to effectively apply the brakes in case another emergency should arise before the air system 40 is restored to normal.

These difficulties are due to the fact that the automatic mechanisms heretofore employed in these air-brake controlling devices, vent the train-line of air pressure in excess 45 of that really necessary to effect the operation desired, and all the excess pressure thus vented, is a waste, and must be restored by the pump on the engine before sufficient pressure can be obtained in the train-line to 50 release the brakes and put the latter in condition for another application.

Another difficulty in the operation of the air-brake mechanism in automatic train-controlling devices arises from the fact that the

pressure utilized in practice for the control 55 of the air-brakes is not uniform, for example;

A freight engine might operate with one hundred pounds pressure in the main reservoir and eighty pounds pressure in the train-line, whereas in passenger service greater pressures are necessary because of higher 60 speed, so that if a valve mechanism is employed that is adjusted for use in freight service that valve would have to be readjusted when the same engine is used in passenger service as is sometimes necessary.

One object, therefore, of my invention is to provide an improved valve device in the air-brake system that will automatically conform 70 to the variation of pressures utilized in the main reservoir and train-line of the system.

A further object is to provide an improved device to automatically control the 75 quantity of train-line pressure that is to escape to the atmosphere and allow only a predetermined amount of pressure to escape, so as to permit a reduction in the train-line of only so much pressure, irrespective of 80 what the train-line pressure may be at the time such reduction is made, so long as there is air pressure in the train-line in excess of that required to be vented to effect an application of the brakes.

85 A still further object of the present invention, is to provide a storage reservoir independent of the main reservoir for compressed air supplied from the air-brake system and to also provide an improved valve 90 device which latter has a piston so that one side of the piston will be subject to the pressure of air contained in the said reservoir while the other side of the said piston will be subject to the pressure and variations of 95 pressure that is in the train-line of the air-brake system, whereby when said train-line pressure has been reduced a predetermined number of pounds, without regard to what pressure the train-line contained in excess of 100 that to be reduced, the escape of additional pressure from the train-line to the atmosphere will be cut off.

With the above, and other objects in view, the invention is illustrated in the accompanying drawings wherein,—

Fig. 1. shows in a diagrammatic way, the engine air-brake equipment and valve de-

vices including my improved vent-control valve.

Fig. 2. illustrates the improved vent control valve in vertical section,—the parts being in the normal running positions.

Fig. 3. shows the same with the parts in the operating position, and

Fig. 4. illustrates a diagram of the track-way and engine circuits.

10 Referring to Fig. 1. of the drawing it will be noted that the engine or vehicle includes the following features or devices in its air-brake equipment, to wit:

15 A main reservoir 5, distributing valve 6, brake-cylinders 7, an engineer's valve 8; pipe connections 9 between the main reservoir 5 and distributing valve 6; pipe connections 10, between the distributing valve 6 and brake cylinders 7, and pipe connections 20 11 between the engineer's valve 8 and the main reservoir 5 and distributing valve 6. It will also be noted that a pipe 12, connects the distributing valve 6 with the train-line and engineer's valve 8, all in the usual manner in the well-known Westinghouse E. T. 6 25 air-brake equipment.

30 In carrying out my invention I also employ with the engine equipment an equalizing or other air-storage reservoir 15, which is charged with air-pressure by a pipe 16, through the engineer's valve 8, from the train line pipe 13 and branch 14, and I further employ what I term a train-line blanking valve 17; a magnet-valve 18, a vent 35 valve 19 and a reset-valve 20, most of which are features that are illustrated in U. S. Patent 1,240,796 granted September 18th, 1917, to Thomas W. Scott.

40 To the above devices I have added my improved automatic vent-control valve 21, which is utilized by me to control the venting of a predetermined amount, of train line pressure through the vent-valve 19, to the atmosphere, and this vent-control valve 21, is interposed somewhere between the train-line and the vent to the atmosphere from the train-line, and is itself subject to the pressure that is contained in the equalizing or 45 other storage reservoir 15. This vent-control valve 21, and its operation and results are novel in train controlling mechanism as will presently be more fully explained.

50 From the main-reservoir pipe 11, I provide a branch 22, which connects with the magnet-valve device 18; I provide a pipe 23 to connect the magnet-valve 18 with the blanking valve 17 and a pipe 24, to connect the magnet-valve 18, with the vent-valve 19. It will thus be understood that all of the 55 pipes 9—11—22—23 and 24 are normally charged with air under main-reservoir pressure.

60 The blanking valve 17, is interposed between the train-line 13 and the engineer's valve 8 by reason of the fact that a cut-out

cock 25, is normally closed in pipe 14, so that the pressure must pass through the engineer's valve 8 by a branch 28 and pipe 27, to the blanking-valve 17, and by pipe 26, from the blanking-valve 17 to the pipe 14. 70 By this means the engineer can only vary the train-line pressure through the blanking valve 17, and if the latter has been cut-off by an automatic operation of the brakes, no manipulation of the engineer's valve can recharge the train-line to release the brakes as long as the blanking valve is cut-off. This feature of operation is set forth in Letters Patent of the United States No. 1,318,925 granted October 14th, 1919; and a detailed 75 description is believed to be unnecessary here.

80 By again referring to Fig. 1. of the drawing, it will be seen that a pipe 29, leads from pipe 14, and connects with the improved vent-control valve 21; that another pipe 30, leads from the vent-control valve and connects with the vent-valve 19, and that a pipe 31, connects the equalizing or other air-storage reservoir 15, with the improved vent-control valve 21.

85 A branch pipe 32, from vent pipe 30, to reset valve 20, is also provided for a purpose presently to be explained.

90 By reference to Figs. 2 and 3 of the drawing wherein the vent-control valve is illustrated, it will be noted that the valve comprises a casing or housing 21, having on its interior a piston 33, which produces an upper chamber 34, and a lower chamber 35, 100 at the opposite sides of the piston. The piston has a stem 36, with a plug valve 37, formed on its lower end which plug valve is designed to cover or uncover a port 38, beneath it that opens into a lower spring 105 chamber 39.

95 In the lower end of the spring chamber 39, there is provided a cylindrical adjusting nut 40, which may be screwed more or less into the end of chamber 39 whereby to vary 110 the length of said chamber.

100 A coiled spring 41 is confined in the chamber 39, and has its lower end seated in the adjusting nut 40, while its upper end is engaged by a central depending pin or stem 115 on the under side of a spring guide 42.

110 This spring guide device has position directly under the port 38, and in the path of the plug valve 37, so that when the piston and its stem move downwardly the valve 37, 120 will contact with the spring-pressed guide 42, and make its final movement against the action of the spring 41. It is to be understood that the guide device 42, is not in any sense a check-valve for port 38, but is simply 125 a perforated disk which serves as a yielding abutment for the lower end of the piston stem and valve. Obviously by vertically adjusting the nut 40, the spring-pressure on the guide 42, may be increased or decreased 130

and after the adjustment has been made a cap 43, on the lower end of the nut will lock the latter in the adjusted position.

From the lower chamber 39, there is a passage 44, with which pipe 30, connects so that said chamber is in communication with the vent-valve 19.

Chamber 35, at the under side of the piston 33, and above the port 38, is in communication with pipe 29, and is therefore subject to the pressure and variations of pressure in the train-line 13, and pipe 14.

It will thus be understood that the plug-valve 37, controls communication between the train-line 13, and the vent-valve 19, and that as the valve 37, is normally open there is a normal communication between the train-line and the vent-valve casing 19.

By again referring to Figs. 2 and 3 of the drawing it will be seen that a passage or groove 45, is formed in the wall of the control-valve chamber which groove extends up at the circumference of the piston 33, so as to feed or allow the pressure on the under side of piston 33, to pass up around the piston to the upper chamber 34.

In some instances where the reservoir or storage receptacle 15, is separate and distinct and has no connection for charging the same through the engineer's valve, the feed groove 45, will also allow train-line pressure to flow from chamber 35, through pipe 31 to the reservoir and charge the latter.

In any event, however, normally the reservoir 15, pipe 31, chamber 34, chamber 35, pipe 29 and pipe 30, are all charged with air at the pressure of the air in the train-line, and it is through the unbalancing of these pressures and reducing the pressure on the under side of the piston 33, that operation of the vent-control valve is effected.

It is important to understand that the spring 41, which forms the yielding abutment for the piston stem and plug-valve and which must be compressed before the plug-valve 37 can seat on port 38, is adjusted to exert a pressure of twenty or twenty-five pounds, more or less, and that this spring pressure is to determine the amount of air, in pounds, that will be permitted to escape or be vented before the venting will be cut-off. In other words, instead of wasting air pressure by venting more than is necessary to effect an application of the brakes, this vent-control valve will permit only so many pounds of air to be vented as is necessary to overcome the action of the spring 41, and when that many pounds of air has been reduced or vented, then the plug-valve 37, will seat and thereby prevent further and unnecessary venting and waste of air-pressure.

Obviously the pressure of the spring 41, is in excess or additional to the air-pressures confined in the several passages and chambers of the valve 21, and while the air-pres-

sures vary, the spring pressure remains the same and may be overcome as long as there is an air-pressure in the valve in excess of the spring pressure.

As is common in train controlling mechanisms to which the present invention is applicable, the automatic operation of the devices on the engine or vehicle is effected through the operation of electrical circuits that are maintained or are interrupted through the movement of a contact shoe which shoe-movement is caused by ramp rails along the trackway. As this feature is not novel in the present invention, a diagrammatic illustration of the circuits and parts included in said circuits is deemed sufficient in connection with a brief description of the same, reference being made particularly to Fig. 4 of the drawing.

The track-rail is designated 46, and is usually insulated at intervals to form trackway sections. Ramp-rails 47, are provided, also at intervals along the trackway, and said ramp-rails are connected with or disconnected from a current-supply 48, through the armature 49, of a relay 50. When the block or section is clear the relay 50, will be energized and one side of the battery 48, will be electrically connected with the ramp-rail 47.

The vehicle carries a contact shoe 51, which latter is connected with a switch 52, which normally engages two contacts 53 and 54. An electromagnet-valve device 18, is carried on the vehicle, as is also a current supply 55, and one side of the current supply is connected by a wire 56, with, say contact 53, while the other side of the current supply is connected to the magnet-valve by a wire 57. The other side of the magnet-valve is connected by a wire 58, to the other shoe-switch contact 54. By means of these connections, as long as switch 52, is closed the electro-magnet valve 18 will be energized and the main-reservoir air-pressure in pipes 22—23 and 24, will be maintained.

A wire connection 59, is also provided on the vehicle to the axle 60, thereof while a branch wire 61, is provided from the shoe 51, to the contact 54.

When the shoe rides up onto a ramp-rail 47, the switch 52, will be opened and the normal circuit from battery 55, through the magnet-valve 18, will be interrupted, but if the track is clear, relay 50, will be energized and armature 49, will be up so that current from the ramp-rail current supply 48, may pass to the ramp-rail; then to the shoe 51; then by wire 61, contact 54 and wire 58 to the magnet-valve 18, which will be kept energized and the return for this picked-up current from the magnet-valve will be by wires 57 and 59 to the axle 60, then through the wheel 62, to track-rail 46, and back to the ramp-rail current-supply 48.

If, however, the track-relay 50, is deenergized, which it would be if the track ahead is occupied, then armature 49, will be down and the connection to the ramp-rail 47, from current supply 48, will be broken so that the shoe 51, cannot pick up current from the ramp.

In this latter event the ramp-rail would operate the shoe and interrupt the normal vehicle circuit thereby deenergizing the valve-magnet 18, and causing an automatic operation to apply the brakes.

This operation is effected as follows:

When magnet-valve 18, is deenergized the valve on the interior thereof will move so as to cut off the main reservoir pipe connection 22, and open a vent from the interior of the magnet-valve to the atmosphere. The opening of this vent exhausts the pressure in the vent valve 19; pipe 24; the pipe 23, and an interior chamber in the train-line blanking valve 17.

The operation in the blanking valve is to cut off connection between the train-line and the engineer's valve 8, so the engineer cannot interfere with the automatic operation of the brakes, but the train-line pressure to the vent-control valve 21, is not affected by any operation in the blanking valve 17.

In the vent valve 19, there is a piston 63, which normally is held down by main reservoir pressure so as to cover ports 64 to the atmosphere. The underside of this vent-valve piston is subject to train-line pressure from pipe 30, and as the main reservoir pressure is always in excess of the train-line pressure, the greater pressure on the upper side of the vent-valve piston 63, will hold that piston down against the lesser train-line pressure in pipe 30. When, however, that greater reservoir pressure on the upper side of the vent-valve piston 63, is vented through the magnet-valve 18, then the train-line pressure on the under side of the piston 63, will move the latter up and uncover the ports 64, so the train-line pressure can and will vent to the atmosphere.

It is right at this moment in the operation of the apparatus that the vent-control valve 21, begins its automatic operation which is the leading feature of the present invention.

Unless some means be provided at this moment in the venting operation the train line will be entirely depleted of its air and release of the brakes cannot be effected and the vehicle allowed to proceed until the air-brake system is recharged. It is to avoid this waste of air-pressure and the consequent loss of time that my improved vent control valve is provided.

By again referring to Figs. 2 and 3 of the drawing it will be noted that when the vent valve 19 is opened to begin venting train-line pressure from pipe 30, that a reduction in the air pressure in pipe 30, chamber 39

and piston-chamber 35, of the vent-control valve 21, will immediately follow, because the vent-control valve is interposed between the train-line and the said vent-valve 19.

Immediately upon a reduction of pressure in chamber 35, of the vent-control valve, the piston 33, will move down until the lower end of its plug-valve stem 37, contacts with the yielding spring-guide 42. This preliminary movement of the piston 33, causes the feed groove 45, to be immediately cut-off so that the pressure in chamber 34, on the upper side of the piston, which pressure is that stored in the reservoir 15, will be in excess of the pressure on the under side of the piston 33. The piston 33, will then be subject to a combined air and spring pressure on the under side, and an air-pressure only, on the upper side so that when the air-pressure on the under side of the piston is reduced until the pressure above is twenty pounds or slightly more than the combined air and spring pressure on the lower side, then the spring will yield under the greater upper pressure and allow the plug-valve to seat over the port 38, and thereby cut-off the flow of air from the pipe 29, and train-line through the chamber 35, so that when the predetermined reduction of train-line pressure, sufficient to apply the brakes has been made, further reduction of train-line pressure will be prevented by the vent-control valve, and waste of air is prevented when the automatic application is made.

After the automatic application and stop has been made the apparatus may be restored to its normal condition by resetting the valve-magnet 18, and again admit main reservoir pressure through pipes 22-23 and 24. When this is done the piston 63, of the vent-valve will move down and close the vent ports 64; the piston in the blanking valve 17, will also be restored to normal by the main reservoir pressure and again establish communication between the train-line and engineer's valve.

As the train-line pressure is then built up, that pressure in pipe 29, and chamber 35, of the vent-control valve will cause piston 33, to move upwardly until the feed groove is uncovered and, if the storage tank 15, is a separate tank, the air will pass by the groove 45, and recharge the storage tank.

It will thus be seen that the pressure of the spring 41, is so utilized that it will limit the quantity of air that is vented from the train-line and when sufficient air to operate the brakes has been vented the spring will yield and allow the plug-valve 37, to cut off and prevent further venting.

Having described my invention, I claim,—

1. In an automatic train controlling mechanism for vehicles the combination

- with a vehicle having an air-brake system including a train-line, a vent device to reduce the pressure in said train-line to effect an application of the brakes, an air-storage reservoir charged from train-line pressure, and a vent-control device having a piston with a connection from one side of the piston to the said storage reservoir, a connection from the other side of the piston 5 to the train-line and a third connection to the said vent device and valve-means actuated by the piston to control communication between the said vent device and that side of the piston which communicates with the train-line.
2. In an automatic train controlling mechanism for vehicles, the combination with a vehicle having an air-brake system including a train-line, a vent device to reduce the pressure in said train-line to effect 10 an application of the brakes, an air-storage reservoir charged from train-line pressure, and a vent-control device having a casing with a chamber and a piston therein and 15 with a valved-outlet at one side of the piston which valved outlet is controlled by the piston, a connection from one side of the piston to the said storage reservoir, a connection between the said valved-outlet and 20 the other side of the piston with the train-line and a third connection from the escape side of the valved-outlet to the said vent device.
3. In an automatic train controlling mechanism for vehicles the combination with a vehicle having an air-brake system 25 including a train-line, a vent device to reduce the pressure in said train-line to effect an application of the brakes, an air-storage reservoir charged from train-line pressure, and a vent-control device having a casing with a piston-chamber and a spring-chamber with a valve between said chambers, a piston in the piston-chamber, a connection from the upper side of the piston to 30 the said reservoir, a connection from the under side of the piston to the train-line, a connection from the spring-chamber to the said vent device, a stem moved by the piston to actuate the valve between the piston and 35 spring-chambers, and a spring in said spring-chamber to press the valve away from its seat.
4. In an automatic train-controlling device for vehicles the combination with a vehicle having an air-brake system including a train-line and a vent means to reduce the pressure in the train-line to effect an automatic application of the brakes; an air-storage reservoir charged with pressure 40 from the train-line; a vent control device independent of the vent means and having a valve that is interposed between the train-line and the said vent means, and a piston device to move said valve said piston device 45 having one side exposed to the train-line pressure during the venting operation and the other side thereof subject to a greater pressure in the said storage reservoir during the venting operation. 70

In testimony whereof I affix my signature.
CHARLES H. QUARLES.
